10 Claims

ABSTRACT OF THE DISCLOSURE

A method of determining the presence of certain constituents in biological samples in which a bag, similar in construction to the well-known flow-thru tea bag, which contains one or more active solid materials used in analytical procedures, is used to capture certain compounds present in the biological product, such as urine or blood, so as to concentrate the compound preferentially, or to bring about a particular type of chemical action such as hydrolysis, or for clarifying solutions.

This invention relates to a method of determining the presence of certain constituents in biological samples. More particularly, the invention concerns a method for use of a bag, similar in construction to the well-known flow-thru tea bag, containing one or more active solid materials used in analytical procedures. The bags are used, for example, to capture certain molecules or compounds present in biological products, especially in animal fluids such as urine or blood, so as to concentrate the compounds preferentially. The method may also be used to bring about a particular type of chemical action such as hydrolysis of glucuronides and sulfates of hormones and drugs in urine prior to extraction, or for clarifying solutions.

The bag is filled with materials such as adsorbents, absorbents, anionic, cationic, or amphoteric ion exchange resins, non-ionic resins, molecular sieves, or water insolubilized enzymes attached to poly(acrylamide) polymers, the material depending on the analytical process to be followed later.

The method has time and cost saving advantages over the methods presently used, such as the use of columns and slurries. The columns must be packed with care, and prepared and washed sequentially. They are also expensive. The slurry method, or the solution method for enzymes, allows for partial or complete loss of material. It is time-consuming to work with methods requiring filtering.

The process of my invention can be carried out completely in the laboratory, or started by an unskilled operator at the collection point. Thus, between the collection point and the laboratory, the particular chemical species one wishes to measure is being adsorbed, adsorbed or ionically or physically trapped for later processing by the technician in the laboratory. The same is true for enzymatic or catalytic hydrolysis.

The method of my invention can also be used in conjunction with the column method by packing the bags into the column for further processing, following the usual procedures.

The bag is made of porous or latticed material such as paper, non-woven plastic or woven man-made fibers. A weighed amount of the resin or other material of appropriate particle size is sealed in the bag. Suitably, a string with a label is attached to the bag for identifying the same. The bag with or without label for identifying the sample may be placed in a separate envelope or packet for protection or for printed instructions. The bag generally is square in shape, although the bottom may con-

2

tain one or more extra folds so as to expand in use, giving greater volume at the lower end. Other shapes may be used. The bag is small in size, a 2" approximately square bag usually being appropriate. The size of the bag is related to the amount of resin required for the volume of liquid sample to be used in the analysis. The bag is filled approximately full unless the resin will swell when placed in the liquid.

The ionic or non-ionic resins are widely varied according to the particular application. Certain types of synthetic resins have considerable exchange capacity. Both cation and anion exchangers can be synthesized which have relatively high capacities for the exchangeable ions. New resins can be "tailor-made" for specific applications requiring certain chemical and physical characteristics. The ion-exchange resins are high molecular weight polymers with ionic groups incorporated in the lattice as integral parts of the polymeric structure. Cation exchangers contain carboxylic, phenolic phosphoric, or sulfonic groups with an equivalent amount of cations. Anion exchangers contain amine groups incorporated in the polymer lattice, neutralized by an equivalent amount of anions such as chloride, hydroxyl, phosphate or sulfate ions. The polymeric portion of the resin has various amounts of cross-linking which affects the solubility.

The general properties of the resin are that it must be sufficiently cross-linked to insure negligible solubility. It should be sufficiently hydrophilic to permit diffusion of ions through the polymer structure at a measurable and usable rate. The structure should be sufficiently stable so as not to degrade during use. Its density should be greater than that of water. The role of particle size in ion-exchange chromatography has been demonstrated to be extremely important. Definite ranges of size can improve results tremendously over use of wide ranges of particle size. Particle size can be sufficiently large that the particles will be contained in the bag without contamination of the sample while testing, and at the same time remain small enough that rapid action occurs with the chemical to be concentrated. These resins are sold under various trademarks such as Amberlite, Dowex, Sephadex, and the like. Amberlite resins are synthetic, high capacity, cation and anion exchange resins, sold by Rohm and Haas, Philadelphia. Dowex 1-X2-Cl is a synthetic strongly basic anion exchange resin containing quaternary ammonium functional groups which are attached to a styrene-divinylbenzene copolymer.

Another use of the process of my invention is to cause hydrolysis of compounds such as glucuronides and sulfates of hormones in urine prior to extraction. The Enzacyrls (a trademark registered by Koch-Light, Ltd, of Colnbrook, Bucks, England) are water insoluble enzymes on hydrophilic carriers based on cross-linked polyacrylamides which contain functional groups potentially active in enzyme binding.

Diatomaceous earth in its various commercial forms can also be placed in the bag for clarifying fluids.

The particle size varies with the material and its use. Amberlite resin XAD-2 has a particle size in the range of about 0.05 to 0.5 mm. diameter, or a screen size of about 275 to 500 wet mesh U.S. Standard.

Two or more bags can be used simultaneously. Thus while just resting in a cup or beaker for various lengths of time, hydrolysis and extraction of selected types of compounds is achieved at the same time, i.e., while the contents of one bag is hydrolyzing molecules, the other bag is picking up the products of the hydrolysis. When the determined time is up the bags are removed and processed further.

Although the bags could be reusable many times after the proper washings, this process is especially useful for a one-time use. Cost is at a minimum because of the

small amount of resin required, and the time of the operator which is saved. For practical purposes, the bag is considered disposable.

According to the process of my invention, samples are prepared for further analysis by the following steps, which is described specifically for a urine sample. However, it is understood that the procedure can be adapted to other biological samples, and body fluids such as blood serum. Following my procedure, a small sample of urine, or other biological fluid which may be diluted if necessary, is placed in a beaker or similar container and the pH adjusted to about 5-6, using dilute alkali or acid, as necessary. Suitable alkalies are sodium hydroxide, sodium carbonate, and sodium bicarbonate; suitable acids include hydrochloric or sulfuric acid.

A small bag made of an inert material such as paper, or woven or unwoven plastic, and containing a resin or adsorbent material is immersed in the liquid. A string attachment having an identifying label may be attached to the bag. The bag is allowed to remain immersed in the liquid for a time sufficient to cause substantial action to take place. The length of time can be substantially shortened by adequate shaking. The reaction with or without shaking can be continued until approximately quantitative action has taken place.

The aqueous liquid is decanted from the bag, and the chemical is recovered from the resin by adding an anhydrous solvent such as acetone, methylene dichloride or ethyl acetate. The solution is dried in any suitable manner. Conveniently, a small bag containing anhydrous sodium sulfate is immersed in the solvent. The pH of the anhydrous solution is adjusted as necessary, and the solution is then evaporated to dryness and the resulting solid material reconstituted with a solvent in order to obtain a solution suitable for analysis, for example, by thin layer chromatography.

EXAMPLE 1

Extraction of drugs from urine using a flow-thru bag containing resin

(1) Place a 20 ml. sample of urine in a 100 ml. container, and adjust to pH 5-6 with a few drops of dilute hydrogen chloride or sodium hydroxide.

(2) Place a moist bag containing 1.8 g. of Amberlite XAD-2 resin into the urine sample. If the bag appears dry, it must be moistened. This can be done by immersing the bag in distilled water and hanging it up to allow the excess water to drip off.

With the bag in the urine at room temperature, shake the container for 7-10 minutes, or allow the bag to remain immersed in the urine for 6-8 hours with no shaking. Shaking can be done, for example, with a mechanical shaker using 1-2" strokes at the rate of 120-200 strokes per minute.

(3) Decant the urine and discard.

(4) Add 15 ml. of acetone to the container with the bag, and swirl or shake for about 5 minutes. Then remove the resin bag. Another bag containing 2.0 g. of anhydrous sodium sulfate is added to the acetone solution to remove residual water. The solution containing the bag is shaken as in step (2) above.

(5) Decant the acetone into another container and adjust the pH to about 2-3 by adding one drop of 1% methanolic hydrogen chloride.

(6) Evaporate the solution to dryness at about 65-70° C., using a water bath in a vented hood. When dry, reconstitute the product with about 50 ml. of methanol to obtain a solution suitable for thin layer chromatography for the separation of drugs.

Other resins can be used depending on the drug to be identified and other variables. In place of acetone, methylene dichloride or ethyl acetate can be used as the anhydrous solvent.

EXAMPLE 2

The bag:

Material—Paper

Shape—Square

Size—1 1/8" x 1 3/8" with heat-sealed edges 3/8" wide

Attachments—String label

Contents—XAD-2 non-ionic resin for drugs, mesh size 200-400 prewashed with methanol (100%) and de-ionized water. The fines are removed by decantation.

COMPARISON OF RECOVERIES BY BAG METHOD AND COLUMN METHOD, PERCENT RECOVERY FROM URINE

	1.8 g. Amberlite XAD-2 resin (dry weight)	1.8 g. XAD-2 resin (dry weight in resin in bag 1 x 5 cm. column)
15		
Morphine.....	40	55-60
Cocaine.....	90-92	60-65
Methadone.....	85-87	80-85
Phenobarbital.....	80-85	20-50
Pentobarbital.....	98-100	45-60
Amphetamine.....	98-100	50-55
Doriden.....	97-100	98-100

Amberlite XAD-2 resin is manufactured by Rohm and Haas Company, Philadelphia, Pennsylvania. It is a synthetic insoluble crosslinked polystyrene polymer which has the following specifications:

	Hard, spherical, water saturated opaque beads	
30	Appearance	
Solids (percent).....	51-55	
Porosity (ml. pore/ml./bead).....	0.40-0.45	
Surface area (m.²/g.-dry basis).....	290-330	
Effective size (mm.).....	0.30-0.45	
Harmonic mean particle size (mm.).....	0.45-0.60	
Average pore diameter (A.).....	85-95	
35	True wet density (g./ml.).....	1.03
Skeletal density (g./ml.).....	1.06	
Bulk density:		
Lbs./ft.³.....	40-44	
G./cc.....	0.64-0.70	

EXAMPLE 3

40 Centrifuge a 10 ml. sample of blood to obtain 4-5 ml. of plasma or serum. Immerse into the serum for about 10 to 60 minutes a small bag containing about 1 g. of a resin or diatomaceous earth or charcoal useful for clarifying the solution and cleaning out the chromophores which interfere with certain analytical procedure due to the presence of too much color. Continue with the usual analytical procedure.

Various modifications and variations of the present invention may be made without departing from the spirit of the discovery or the scope of the appended claims.

What is claimed is:

1. In an analytical procedure for determining the presence of certain constituents in biological samples, the step of immersing one or more flow-thru bags, each containing a premeasured amount of a solid reactive material into an aqueous biological fluid for a time sufficient for reaction to take place, and then removing the bag from the liquid to effect a separation of certain of said constituents.

2. The step of claim 1 wherein said solid reactive material is a non-ionic resin for the absorption of water soluble drugs from urine.

3. The step of claim 1 wherein said solid reactive material is a diatomaceous earth material useful for clarifying blood serum prior to further analysis.

4. The step of claim 1 wherein said solid reactive material is a water insoluble enzyme on a hydrophilic carrier based on cross-linked poly(acrylamides) which contain functional groups potentially active in enzyme binding.

5. A method for the analysis of urine which comprises the steps of:

(a) adjusting the pH to about 5-6;
 (b) immersing in the sample a flow-thru bag moistened with water containing a non-ionic resin for the absorption of water soluble organic substances, and

allowing the bag and sample to stand for 6-10 hours without shaking, or for 7-10 minutes with shaking; (c) decanting the aqueous liquid and discarding it; (d) extracting the material to be analyzed from said resin using an anhydrous solvent, and then dehydrating the solution and adjusting it to a pH of about 2-3; (e) evaporating said solution to dryness and reconstituting the dry product with a solvent to obtain a solution suitable for chromatographic analysis.

6. The method of claim 5 wherein the resin is a non-¹⁰ ionic resin for drugs.

7. The method of claim 5 wherein the particle size of the resin is in the range of about 0.05 to 0.5 mm. in diameter, and the screen size is about 275 to 500 wet mesh U.S. Standard.

8. The method of claim 5 wherein the solution in step (d) is dehydrated by use of a bag containing anhydrous sodium sulfate.

9. The method of claim 5 using an ionic exchange resin. 10. The method of claim 5 wherein the dry product in step (e) is reconstituted with a solvent suitable for thin layer chromatographic analysis to determine the presence of drugs.
